UNITED STATES PATENT OFFICE.

WILLIAM BRANNAN, OF NEWARK, NEW JERSEY.

UNDERGARMENT.

1,231,482.

Specification of Letters Patent. Patented June 26, 1917.

Application filed August 29, 1916. Serial No. 117,511.

To all whom it may concern:

Be it known that I, WILLIAM BRANNAN, a citizen of the United States, residing at Newark, in the county of Essex and State 5 of New Jersey, have invented new and useful Improvements in Undergarments, of which the following is a specification.

This invention relates to an undergarment which is especially adapted to be worn 10 by women having nursing infants or during the period of gestation to serve as a brassière.

The primary object of the invention is to provide an undergarment of this character 15 which is in the form of an under body and has formed in the front thereof upon opposites side of the fastening fly openings adapted to be closed by flaps so arranged with relation to each other and connected with the 20 undergarment in such a manner that under normal conditions the flaps serve as pouches in which the breasts are supported and when partially disconnected from the undergarment allow the breasts to be passed through 25 said openings for nursing purposes.

A further object of the invention is to provide an under body of this character in which a pair of front sections containing the breast supporting flaps are connected with 30 a back section through the medium of shoulder loops and lacings threaded through eyelets in lacing flies at the sides of the front and back sections and extending from the arm openings to the waist line of the undergarment, thus rendering the garment extensible and especially serviceable for use of 35 women during the gestation period.

With these and other objects in view, the invention resides in the novel combination 40 and arrangement of parts which will be hereinafter described and particularly pointed out in the claims.

The preferred embodiment of the invention has been illustrated in the accompanying 45 drawing, although no restriction is necessarily made to the precise details of construction therein shown, as changes, alterations and modifications within the scope of the claims may be resorted to when desired.

Like characters of reference denote corresponding parts throughout the several views in the drawing, in which:

Figure 1 is a view in elevation of an undergarment constructed in accordance with

the invention, the front sections thereof being shown in extended position.

Fig. 2 is a view in elevation of the improved undergarment and showing the front sections in normal position with one of the 60 flaps thereon partly raised.

Fig. 3 is a fragmentary vertical transverse section through one of the front sections.

Referring now to the drawing in detail, 65 the numeral 1 designates the improved undergarment as a whole which comprises a back section 2 permanently connected with front sections 3 and 4 through the medium of shoulder loops 5, providing the undergarment with arm holes 6.

The opposed side edges of the front and back sections are provided with lacing flies 7 extending from the arm holes to the waist line of the undergarment and containing 75 flexible stiffening strips 7', said flies are provided with eyes 8 through which are passed laces 9 and by means of which the undergarment is rendered extensible. The free side edges of the front sections 3 and 4 are 80 provided with fastening flies 10, the fly 10 on the front section 3 being adapted to overlie the fastening fly 10 on the front section 4 and is provided with a row of fastening elements 11 adapted to be engaged with suitable fastening elements 12 on the fly 10 of the section 4.

Each of the front sections 3 and 4 comprises an upper member 13 and a lower member 14 arranged in spaced relation and 90 connected by the flies 7 and 10 on said sections in such a manner that an opening 15 is formed therein midway between the neck and waist line of said section and extending transversely between said flies, said upper 95 section being of such length and shape as to provide a closing flap 17 for said opening.

The flies 7 and 10 adjacent the openings 15, and the upper edge of the lower sections 14 are provided with fastening members 18 100 adapted to be engaged by suitable fastening members 19 on the inner faces of the closing flaps 17 adjacent the free edges thereof, said flaps having formed therein darts 20 which when the flaps are in closed position 105 enable the same to assume the shape of pouches for a purpose which will herein-after appear.

The upper side edge of each lower section 14 has secured thereto the lower edge 110

of a supporting flap 22, the ends of which are connected with the flies 7 and 10 on the front sections with the upper edge of the flap arranged adjacent to the lowermost dart 20 in the closing flaps 17, said supporting flaps 22 being provided with draw strings 23, by means of which the supporting flaps may be shaped in the form of a pouch to correspond to the shape of the pouch formed by the closing flaps 17 in which the supporting flaps are adapted to be arranged. The supporting flaps 22 are preferably formed of net so that the pouches formed by the flaps may be properly ventilated.

15 From the above described manner of arranging and connecting the flaps 17 and 22 with the upper and lower members of the front sections, it will be seen that under normal conditions the flaps serve as pouches

20 for supporting the breasts, and that when it is desired to pass the breasts through the openings 15 for nursing purposes, the closing flaps 17 may be disconnected from the flies 7 and 10 and the lower members 14 and

25 the flaps 22 removed from the breasts.

When the flaps 17 and 22 are again restored to their normal position, it will be seen that the openings 15 will be closed and that said flaps will serve as an effective support for the breasts, while the laces 9 which connect the front and back sections permit the extension of the undergarment when worn during the period of gestation. The draw strings 23 permit the size of the pouches to be regulated during and after the period of pregnancy.

From the foregoing description taken in

connection with the accompanying drawing, it is at once apparent that an undergarment has been provided which though simple in construction and, therefore, inexpensive of manufacture, is highly efficient in use.

Having thus described the invention, what is claimed as new, is:—

1. An undergarment comprising a back section, front sections arranged upon opposite sides of the back section and adjustably connected therewith and including upper and lower members arranged in spaced relation to provide openings therein, flies connecting said upper and lower members, closing flaps for said openings on said upper sections removably connected with said flies and the lower sections, and supporting flaps underlying said closing flaps and connected with the lower sections and flies. 45

50

55

2. An undergarment comprising a back section, front sections arranged upon opposite sides of the back section and including upper and lower members arranged in spaced relation to provide openings in the front sections, flies connecting said upper and lower members, means for adjustably connecting said front sections with the back section, flaps on the upper members for closing said openings removably connected with said flies and the lower members, supporting flaps having connection with the lower members and flies and underlying the first mentioned flaps, and means for forming 60 pouches of the flaps connected with the lower members and flies. 65

70

In testimony whereof I affix my signature.

WILLIAM BRANNAN.
